UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SOCKET.

Application filed July 30, 1924. Serial No. 729,025.

To all whom it may concern:

Be it known that I, REUBEN B. BENJAMIN, a citizen of the United States, residing at Chicago, in the county of Cook and State 5 of Illinois, have invented new and useful Improvements in Sockets, of which the following is a full, clear, concise, and exact description, reference being had to the accompanying drawing, forming a part of this 10 specification.

This application comprises a continuation in part of applicant's co-pending application Serial No. 400,064 filed July 30, 1920.

My invention relates to sockets and more 15 particularly to shock-absorbing sockets for use in radio apparatus.

One of the objects of my invention is to provide an improved shock-absorbing socket, which will be durable and efficient in use, 20 simple in construction and cheap to manufacture.

Another of the objects of my invention is to provide a socket having an improved form of contact for engaging the electrodes of a 25 vacuum tube, which will insure a good electrical connection.

Further objects will appear from the description and claims.

In the drawings in which an embodiment 30 of my invention is shown.

Fig. 1 is a plan view of a shock-absorbing socket;

Fig. 2 is a side elevation of the socket;

Fig. 3 is a bottom view of the socket, 35 parts being broken away to show the underlying construction;

Fig. 4 is a section on the line 4-4 of Fig. 1;

Fig. 5 is a perspective view of a contact 40 and spring member;

Fig. 6 is a perspective view of a contact member, and

Fig. 7 is a perspective view showing how 45 the members shown in Figs. 5 and 6 are assembled.

Referring to the drawings in detail, the construction shown comprises an insulating wiring base 10, a cylindrical insulating supporting or receptacle shell 11 for receiving 50 vacuum tubes, wiring terminals 12 mounted on the insulating base, means for yieldingly supporting the shell on the wiring base, and spring contact devices 13 for engaging the electrodes of the vacuum tube.

55 In a type of vacuum tube in common use,

the electrodes are in the form of pins extending longitudinally of the axis of the tube. Each of the contact devices for engaging one of these pins comprises a leaf spring member 14 extending radially of the socket, and engaged by the end of the pin as the tube is inserted and a leaf spring member 15 juxtaposed with respect to the leaf spring contact member 14, and having an upwardly bent spring tip portion 16 extending through 65 the opening 17 in the spring contact member 14 for engaging the side of the electrode pin as the tube is given a slight movement of rotation to effect a connection with the bayonet joint slot 18 of the tube receiving shell. 70

The upwardly extending tip 16 of the leaf spring contact member 15 is provided with an inclined approach portion 19 for facilitating the proper engagement of the electrode pin and contact tip. As the tube is given 75 its slight movement of rotation, the electrode pin engages the inner face of this inclined approach portion and presses the tip of the contact outwardly, causing the tip to exert a spring pressure on the side of the pin 80 to insure a good electrical connection.

By means of the two spring contact members, an electrical connection is effected, both with the end and with the side of the 85 electrode pin.

In order to yieldingly support the tube receiving shell, a plurality of cantilever leaf spring members 20 are provided which, as shown, may be formed integrally with the spring contact members 14, and which are secured to and extend substantially along 90 and beneath the peripheral edge of the receptacle shell and to the wiring base, eyelets 21 being used to hold the springs against lug portions formed on the shell. 95

If desired and as shown, the wiring terminals may be formed as extensions of the stamping from which the leaf-spring members 20 are formed.

While I have shown but one form of my 100 invention, it is obvious that it may be embodied in other forms covered and defined by the appended claims.

I claim:

1. A socket having contact devices for engaging the electrodes of an insertable device, the electrodes of the insertable device including pins extending longitudinally of its axis and said device being connectable with the socket by a movement including a 110

- turning movement, each contact device comprising a spring member yieldable longitudinally of the pin for engaging the end of the pin, and another spring member for 5 engaging the side of the pin yieldable laterally of the pin and substantially independently of the longitudinally yieldable spring member.
2. A socket having contact devices for 10 engaging the electrodes of an insertable device, the electrodes of the insertable device including pins extending longitudinally of its axis, each contact device comprising a spring member yieldable longitudinally of 15 the pin for engaging the end of the pin, and another spring member for engaging the side of the pin yieldable laterally of the pin and substantially independently of the longitudinally yieldable spring member.
- 20 3. A socket having contact devices for engaging the electrodes of an insertable device, the electrodes of the insertable device including pins extending longitudinally of its axis, each contact device comprising a member for 25 engaging the end of the pin, and another member formed separately from the first for engaging the side of the pin.
4. A socket having contact devices for 30 engaging the electrodes of an insertable device, the electrodes of the insertable device including pins extending longitudinally of its axis, said insertable device being connectable with the socket by a movement including a turning movement, the contact device 35 for each electrode comprising a cantilever leaf spring member for engaging the end of the pin and a separately formed cantilever spring member for engaging the side of the pin.
- 40 5. A socket having contact devices for engaging the electrodes of an insertable device, the electrode of the insertable device including pins extending longitudinally of its axis, said insertable device being connectable with the socket by a movement including a turning movement, the contact device for each electrode comprising a substantially radially extending cantilever leaf 45 spring member for engaging the end of the pin and another cantilever leaf spring member with a longitudinally extending portion for engaging the side of the pin, said radially extending leaf spring having a hole through which said longitudinally extending portion extends.
- 50 6. A socket having contact devices for engaging the electrodes of an insertable device, the electrodes of the insertable device including pins extending longitudinally of its axis and said device being connectable with the socket by a turning movement, the contact device for each electrode comprising two juxtaposed radially extending cantilever leaf spring members, the tip of 55 one leaf spring member engaging the end of the pin and the tip of the other engaging the side of the pin.
7. A socket having contact devices for engaging the electrodes of an insertable device, the electrodes of the insertable device including pins extending longitudinally of its axis and said device being connectable with the socket by a movement including a turning movement, the contact device for each electrode comprising two juxtaposed radially extending cantilever leaf spring members, the tip of one leaf spring member engaging the end of the pin and the tip of the other engaging the side of the pin, said socket comprising a shell, and a rivet extending through both said leaf spring members for securing them to said shell. 70
8. A socket having contact devices for engaging the electrodes of an insertable device, the electrodes of the insertable device including pins extending longitudinally of its axis and said device being connectable with the socket by a movement including a movement of rotation, each contact device comprising a cantilever leaf spring member 75 for engaging the end of the pin and a cantilever spring member acting independently for engaging the side of the pin, said last spring member having an inclined approach portion for insuring the proper engagement of the leaf spring member and electrode. 80
9. A socket having contact devices for engaging the electrodes of an insertable device, the electrodes of the insertable device including pins extending longitudinally of its axis, each contact device comprising a member for engaging the end of the pin, and another member formed separately from the first for engaging the side of the pin, said 85 contact members being formed with inter-engaging means providing limited independent movement of the contact-making portions thereof. 100
10. A shock-absorbing socket comprising a contact, and a yielding support and wiring terminal construction for said contact comprising a sheet metal member having a leaf spring portion bearing on said contact, and a binding plate portion. 110
11. A shock-absorbing socket construction for delicate electrical apparatus comprising an insulating support, wiring terminals mounted thereon, a substantially cylindrical receptacle construction comprising an insulating base and contacts for the apparatus mounted thereon, and means for yieldingly supporting said receptacle construction with respect to said insulating support, comprising a plurality of spaced leaf-spring members between the insulating base and insulating support acting on the socket construction adjacent the periphery thereof, and extending substantially circumferentially with respect to the periphery of the socket construction. 115
- 120
- 125
- 130

12. A shock-absorbing socket construction for delicate electrical apparatus comprising an insulating support; a receptacle comprising an insulating base construction and contacts mounted thereon, and a wiring terminal and yielding support construction comprising an integral sheet metal member having a terminal portion mounted on said insulating support, and a leaf spring portion acting on the receptacle construction adjacent the periphery thereof. 70
13. A shock-absorbing socket construction for delicate electrical apparatus comprising an insulating support, wiring terminals mounted thereon, a substantially cylindrical receptacle construction comprising an insulating base and contacts mounted thereon, and means for yieldingly supporting said receptacle construction with respect to said insulating support, comprising a plurality of spaced leaf-spring members acting on the socket construction adjacent the periphery thereof and extending substantially circumferentially with respect to the periphery of the socket construction. 80
14. A shock-absorbing socket construction for delicate electrical apparatus comprising a wiring base, a receptacle unit and shock-absorbing means for yieldingly supporting said receptacle unit with respect to said wiring base, said wiring base comprising an insulating base and wiring terminals mounted thereon, said receptacle unit comprising contacts and insulation for positioning said contacts with respect to each other, said base and unit having opposed adjacent complementary faces, and said shock-absorbing means comprising a plurality of leaf spring members arranged between and extending substantially flatwise of said opposed faces. 90
15. A shock-absorbing socket construction for delicate electrical apparatus comprising a wiring base, a receptacle unit, and shock-absorbing means for yieldingly supporting said receptacle unit on said wiring base, said wiring base comprising an insulating base and wiring terminals mounted thereon, said receptacle unit comprising contacts and insulation for positioning said contacts with respect to each other, said base and unit having opposed adjacent complementary faces, and said shock-absorbing means comprising a plurality of leaf-spring members arranged between and extending substantially flatwise of said opposed faces, said leaf-spring members being of conducting material and electrically connecting one of said wiring terminals and one of said contacts. 100
16. A shock-absorbing socket construction for delicate electrical apparatus comprising a base, a cylindrical receptacle member for receiving the apparatus, and shock-absorbing means for yieldingly supporting said receptacle member on said base comprising a plurality of cantilever spring members mounted on said base and acting on said receptacle member adjacent the periphery thereof and extending substantially circumferentially with respect thereto. 110
17. A shock-absorbing socket construction for delicate electrical apparatus comprising a wiring base, a receptacle member for receiving the apparatus, wiring terminals for the electrical apparatus mounted upon the base, and a shock-absorbing means for yieldingly supporting said receptacle member in equipoise on said base comprising at least three cantilever spring members acting between said base and said receptacle member to provide a relatively stable area of support, each spring having one end fixed against movement in respect to the base, and means for holding said receptacle member firmly against the other ends of said springs. 120
18. A shock-absorbing socket construction for delicate electrical apparatus comprising a base, a substantially cylindrical receptacle member for receiving the electrical apparatus, means on the receptacle member for engaging the electrical apparatus by a turning movement of the latter, and means for yieldingly supporting said receptacle member upon said base comprising a plurality of leaf springs between the base and the receptacle disposed in the region beneath and extending substantially along the peripheral edge of said receptacle. 130
19. A shock-absorbing device for delicate electrical apparatus comprising a receptacle member, a wiring base, and a plurality of conductor springs, each connected to the wiring base and forming circuit connectors for the apparatus, and each lying substantially in a plane transverse to the axis of the receptacle member. 140
20. Supporting means for delicate electrical apparatus comprising a receptacle shell supported by at least three conductor springs subtending the perimeter of said shell and providing a shock-absorbing but relatively stable area of support and also forming circuit connectors for the electrical apparatus. 150
21. A shock-absorbing device for electrical bulbs and the like, comprising a base, means thereon for receiving leading-in conductors, a bulb-supporting unit having contacts for engagement with the terminals of the bulb with provision for electrically connecting the said contacts with the leading-in conductors, and resilient means for yieldingly supporting the said unit with respect to the base, said means having spring members disposed about the axis of the unit and in a plane substantially parallel with the plane of the rear face of the unit. 160
22. A shock-absorbing device for electrical bulbs and the like, comprising a base, a tubular bulb receiving receptacle, the base

extending inwardly of the outer margin of the receptacle, and resilient means to cushion the unit with respect to the base comprising leaf springs interposed flatwise between the adjacent faces of the base and the receptacle.

23. A shock-absorbing device for electrical bulbs and the like, comprising a base having conductor terminals for leading-in wires, a bulb-supporting device closely spaced but movable with respect to the base and having contacts for the bulb terminals, and conducting means between the terminals on the base and the contacts on the bulb-supporting device for holding the latter in equipoise and 10 also for supplying current to the bulb carried by the bulb-supporting device, said conducting means including leaf springs react-

ing between and disposed laterally of the space between the base and the bulb-supporting device. 20

24. A base having terminals for leading-in wires, a bulb-supporting member carried by the base and having contacts associated with the terminals on the base, and a relatively flat cushioning means between the base and the bulb-supporting member having a plurality of leaf springs, at least one of which electrically connects one of the terminals on the base with an associated bulb contact on the bulb-supporting member. 25 30

In witness whereof, I have hereunto subscribed my name.

REUBEN B. BENJAMIN.
